UNITED STATES PATENT OFFICE.

LYMAN W. WELCH, OF MONTPELIER, VERMONT.

WARDROBE-BEDSTEAD.

SPECIFICATION forming part of Letters Patent No. 311,623, dated February 3, 1885.

Application filed March 4, 1884. (No mod. 1.)

To all whom it may concern:

Be it known that I, LYMAN W. WELCH, a citizen of the United States, residing at Montpelier, in the county of Washington and State 5 of Vermont, have invented new and valuable Improvements in Wardrobe-Bedsteads; and I do hereby declare the same to be described in the following specification, and represented in the accompanying drawings.

10 My invention consists in a wardrobe-bedstead which may be lowered to the floor while in use, and folded closely to the wall at other times.

Figure 1 is a perspective view showing the 15 curtain and the bedstead when lowered to the floor. Fig. 2 is a side view showing the side piece or casing in dotted lines, the fixed pulley, the flexuous cord, cable, or chain, the clamp around the same, the case or spring- 20 receptacle attached to the side piece or casing, the bed-frame stop, and the bed-frame, with anti-friction pulley attached, and track therefor. Fig. 3 is a sectional view showing the fixed pulley, the flexuous means of suspension, the clamp, the spring-receptacle, 25 and the coiled spring suspended therein. Fig. 4 is an end view of the bed-frame, showing the anti-friction pulleys. Fig. 5 is a front view of the curtain-pole and curtain covering the 30 bedstead when the same is folded to the wall.

Like letters of reference refer to like parts in the several figures.

The letter *a* represents the head-board, securely fastened to the wall, and having attached to each end the casings *b b*.

35 *c c* represent fixed pulleys, one of which is firmly fastened to the inside of each of the casings aforesaid, and over which the flexuous cords, cables, or chains *g g* run when the bed- 40 stead is being raised or lowered.

d represents the bed-frame, supported at the foot end by the foot-board and legs combined, *e*, and suspended at the head end by the flexuous cords, cables, or chains from the fixed 45 pulleys.

g g represent the cords, cables, or chains, which may be made of any suitable material, and are attached to the bed-frame at *h h h* by means of a button attachment. When the 50 bedstead is folded up, the foot-board *e* is turned out in prolongation of the bed-frame *d*.

f represents the pivot upon which the foot-board is turned, the top being turned down and outward, and the bottom being turned in and upward.

55 *i i* represent the cases or spring-receptacles, securely fastened to the inside of the casings *b b*, immediately below the fixed pulleys *c c*, and each containing the coiled springs *j j*. These springs are suspended from the top of 60 the cases or spring-receptacles, and when the bedstead is being lowered and the cords, cables, or chains pass over the fixed pulleys, the clamps *k k*, around the flexuous cords, cables, or chains, pass upward and meet the 65 bottoms of the springs *j j*, compressing them together and accumulating power which is utilized in again folding the bedstead to the wall.

70 *l l* represent the anti-friction pulleys, one of which is attached to each side of the bed-frame near the head end.

n n represent the curved tracks, attached to each casing on the inside, and are for the anti-friction pulleys *l l* to run upon in raising or 75 lowering the bed.

m represents the end of the bed-frame, boxed so as to be filled with any suitable weight, which serves to counterbalance the bed-frame *d*.

80 *o o* represent the bed-frame stops, which consist of brackets, one of which is fastened on the inside of each of the casings *b b*, and support and keep the bed-frame firmly in position when the bedstead is lowered.

85 *p* represents the curtain-pole above the head-board, hung upon brackets from the wall, upon which the curtain *r* is drawn when the bedstead is folded up.

Having thus fully described my invention, 90 what I claim is—

1. In a wardrobe-bedstead, the combination of the head-board *a* with the casings *b b*, provided with the fixed pulleys *c c*, and the bed-frame *d*, provided with the flexuous cords, 95 cables, or chains *g g*, which pass over the fixed pulleys *c c*, all constructed to operate substantially as set forth and described.

2. In a wardrobe-bedstead, the combination of the head-board *a*, and the casings *b b*, provided with the springs *j j*, and the fixed pulleys *c c*, with the bed-frame *d*, said bed-

frame being provided with flexuous cords, cables, or chains *g g*, which pass over the fixed pulleys *c c* and through the springs *j j*, and to which are attached lugs or stops *h h*, to engage 5 said springs, all constructed to operate substantially as shown, and for the purposes described.

3. In a wardrobe-bedstead, the combination of the bed-frame *d*, having the weighted 10 box end *m*, and the anti-friction pulleys *l l*,

with the head-board *a*, and the casings *b b*, said casings having attached the fixed pulleys *c c*, the springs *j j*, and the tracks *n n*, all constructed to operate substantially as shown, and for the purposes described.

LYMAN W. WELCH.
